VALVE TRAIN ASSEMBLY FOR INTERNAL COMBUSTION ENGINES

John Chadwell, Cincinnati, Ohio

Application March 22, 1957, Serial No. 647,831

4 Claims. (Cl. 123—90)

This invention relates in general to new and useful improvements in internal combustion engines and more specifically to an improved valve train assembly.

At the present time, the return springs for the valve of internal combustion engines are disposed concentric with the valve stems and are connected directly to the valves for the purpose of urging the valves to closed positions. However, the position of the springs is such that a large amount of heat is transferred to the springs, thus causing rapid deterioration of the springs with the result that the valves do not properly seat at high speeds after the internal combustion engine has been run for a period of time.

It is therefore the primary object of this invention to provide a valve train assembly for internal combustion engines wherein the return spring for the valve is positioned remote from the valve so as to eliminate the effect of heat on the valve spring, the valve spring being disposed in engagement with the rocker arm for the particular valve so as to urge the valve to a closed position through the rocker arm.

Another object of this invention is to provide an improved valve train assembly for internal combustion engines wherein the rocker arm is provided with a fitting which permits the positive connection of a valve stem to the rocker arm and at the same time permits freedom of rotation of the valve so as to prevent burning thereof and to insure proper seating of the valve.

Another object of this invention is to improve valve train assembly for internal combustion engines, the valve train assembly including a rocker arm which is positively connected to a valve and which has engaged therewith a spring whereby the rocker arm is positively urged towards a valve closing position by the spring and the valve is urged to such a closed position by its positive connection with the rocker arm.

Another advantage of the present invention is that the construction thereof is such that the rocker arms may be constructed to have a greater ratio in order to effect a greater travel of the valve, thus increasing the valve opening and effecting better breathing of the internal combustion engine.

Another object of this invention is to provide an improved fitting for positively connecting a valve stem to a rocker arm, the fitting including a ball member having a rod extending from one end thereof for attachment to the rocker arm and a socket fitting having a rod extending from it in a direction generally opposite to the direction of the first mentioned rod, the second mentioned rod being adapted for positive attachment to a valve stem.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a fragmentary sectional view taken through the head construction of an internal combustion engine

2

of the overhead valve type and shows the valve train assembly which is the subject of this invention;

Figure 2 is an enlarged, vertical, sectional view taken through the fitting connecting the rocker arm to the valve stem and shows the specific details of construction of that fitting;

Figure 3 is an enlarged, sectional view taken substantially upon the plane indicated by the section line 3—3 of Figure 2 and shows further the details of construction of the socket member of the fitting;

Figure 4 is an enlarged, fragmentary, elevational view of one end of the rocker arm and shows the details of the spring connection therewith;

Figure 5 is an enlarged, fragmentary, sectional view taken substantially upon the plane indicated by the section line 5—5 of Figure 4 and shows the relationship of hold-down bolts for the spring;

Figure 6 is a fragmentary, sectional view similar to Figure 1 and shows a modified form of the invention;

Figure 7 is an enlarged, fragmentary, sectional view showing the adjustable connection between the rocker arm and the push rod; and

Figure 8 is an enlarged, fragmentary, sectional view showing the connection between the spring retainer and the rocker arm.

Referring now to the drawings in detail, it will be seen that there is illustrated in Figure 1 a portion of an internal combustion engine which is of the overhead valve type, the internal combustion engine being referred to in general by the reference numeral 10. The internal combustion engine 10 includes a block 12 having a cylinder 14. Overlying the block 12 is a head 16 which is provided in a combustion chamber 18 in alignment with the cylinder 14. Extending through the head 16 for selective communication with the combustion chamber 18 is a gas passage 20 which may be used for the entrance of a fuel-air gas mixture into the combustion chamber 18 or for exhaust gases. The flow of gases through the passage 20 is controlled by a valve 22 which includes a head 24 and a valve stem 26. The valve stem 26 is guidingly disposed in a bore 28 in the upper part of the head 16 and projects above the head 16.

In order to effect the actuation of the valve 22, the block 12 is provided with a bore 30 which is aligned with a bore 32 in the head 16. The bores 30 and 32 have freely passing therethrough an elongated push rod 34 whose lower end is engaged with a follower (not shown) which is in turn engaged with a cam shaft (not shown) for vertical reciprocatory movement. It is to be noted that the push rod 34 extends upwardly above the head 16 a considerable distance.

Carried by the head 16 and projecting thereabove is the valve train assembly which is the subject of this invention, the valve train assembly being referred to in general by reference numeral 36. The valve train assembly 36 includes a plurality of longitudinally spaced, upstanding rocker arm shaft supports 38, only one of the supports 38 being illustrated. Extending longitudinal of the head 16 is a rocker arm shaft 40 which is supported by the supports 38. Mounted on the rocker arm shaft 40 for rocking movement is a plurality of rocker arms 42. It is to be understood that there is one rocker arm 42 and one push rod 34 for each of the valves 22.

Carried by the underside of the rocker arm 42 at one end thereof is an adjustable fitting 44 for engagement with the upper end of the push rod 34 so that the push rod 34 may urge the rocker arm 42 to rock or rotate in a clockwise direction. The fitting 44 is adjustable so as to permit adjustment of the valve train as is necessary. It is to be understood that the fitting 44 may be of a conventional type.

In order that the rocker arm 42 may control the posi-

tion of the valve 22, there is provided a fitting which is referred to in general by the reference numeral 46. The fitting 46 is carried at the opposite end of the rocker arm 42 from the fitting 44 and is connected to the underside thereof. The fitting 46 is also connected to the upper end of the valve stem 26. The details of the fitting 46 will be set forth hereinafter.

In order that the valve 22 may be continuously urged towards a closed position, there is provided a spring assembly which is referred to in general by the reference numeral 48. The spring assembly 48 includes a cup-shaped lower bearing member 50, as is best illustrated in Figure 4, which overlies the one end of the rocker arm 42 generally in alignment with the fitting 44. Seated in the retainer 50 is a heavy duty coil spring 52 of the general type used in conjunction with valves for returning of the valves to closed position. Overlying the upper end of the spring 52 is an inverted, cup-shaped retainer 54. The spring 52 is retained in a compressive state by means of a plate 56 which overlies the retainer 54. The plate 56 is positioned relative to the head 16 by means of a plurality of elongated bolts 58 whose lower ends are anchored in the head 16 and whose upper ends are provided with nuts 60 adjustably threadedly engaged thereon. By adjusting the nuts 60, the spring 52 may be adjustably positioned and the compression thereof slightly varied. Inasmuch as the spring 52 urges downwardly on the left end of the rocker arm 42, as viewed in Figure 1, it will be readily apparent that the right end of the rocker arm 42 is urged upwardly so as to pull the valve 22 to a closed position.

Referring now to Figures 2 and 3 in particular, it will be seen that there is illustrated the details of the fitting 46. The fitting 46 includes a ball member 62 which has secured thereto an elongated rod 64 whose opposite end is externally threaded as at 66. The right-hand end of the rocker arm 42, as viewed in Figure 1, has the lower part thereof provided with an internally threaded bore 68 in which the threaded portion 66 is threaded engaged. The rod 64 is retained in an adjusted position relative to the rocker arm 42 by means of a lock washer 70 and a lock nut 72, the lock nut 72 being engaged with the threaded portion 66.

The fitting 46 also includes a socket member which is referred to in general by the reference numeral 74. The socket member 74 includes an upper half 76 and a lower half 78. The halves 76 and 78 are of identical construction with the exception that the upper half 76 is provided with an opening 80 for the passage of the rod 64 and there is secured to the lower half in alignment with the center of the opening 80 an externally threaded rod 82. The rod 82 is received in an internally threaded bore 84 in the upper end of the valve stem 26. The rod 82 is locked in the bore 84 by means of a lock washer 86 and a lock nut 88.

Inasmuch as the halves 76 and 78 are identical with the exceptions set forth above, only the half 78 will be described in detail. The half 78 includes a semi-spherical shell 90 which is provided with an annular connecting flange 92. The connecting flange 92 of the halves 76 and 78 are connected together by a plurality of circumferentially spaced fasteners 94.

Each of the halves 76 and 78 also includes a generally semi-spherical ball retainer 96 which is disposed within the confines of the shell 90 and are concentric relative thereto. The ball retainer 96 is provided with a plurality of openings 98 for the passage of portions of a plurality of balls 100 which are disposed between the ball retainer 96 and the shell 90. The balls 100 are so disposed whereby they engage the ball member 62 so as to position the socket member 74 thereon. It is to be noted that the ball retainer 96 is provided with a plurality of radiating sockets 102 which are internally threaded and which have received therein fasteners 104 carried by the shell 90. The fasteners 104 serve to position the ball retainer 96

relative to the shell 90 and also facilitate the assembly of halves 76 and 78.

Although the rod 64 has been illustrated and described as being connected to the rocker arm 42 and the rod 82 has been illustrated and described as connected to the valve stem 26, it is to be understood that the fitting 46 may be inverted from its position in Figure 2.

By placing the spring assembly 48 remote from the head 16, the high temperatures of the head 16 no longer affect the spring 52. This assures a long life of the spring 52, as well as a constant spring pressure on the valve 22. On the other hand, the detrimental features normally resulting from the shifting of the valve spring are eliminated by providing the fitting 46. The fitting 46 not only serves to positively actuate the valve 22, but also permits relative rotation between the valve 22 and the rocker arm 42 even though the two are positively connected together.

The particular arrangement of the components of the valve train assembly 36 is such that the rocker arm 42 may extend further to the right, as viewed in Figure 1, than usual. By so increasing the length of one end of the rocker arm 42, the ratio of the rocker arm 42 is changed, and thus the valve 22 may be moved a greater distance for a like movement of the push rod 34. By increasing the opening of the valve 22, a greater flow of gases past the valve 22 is permitted, thus increasing the efficiency of the internal combustion engine 10.

The entire valve train assembly is covered by a rocker arm cover 106 of the usual type which is sealed with respect to the head 16 by means of a gasket 108 to prevent leakage of oil which is used to lubricate the valve train assembly. The cover 106 is retained in place by fasteners 110.

Referring now to Figures 6, 7 and 8 in particular, it will be seen that there is illustrated a modified form of valve train which is referred to in general by the reference numeral 112. The valve train 112 is mounted on a head 114 which includes a plurality of valves, both intake and exhaust, only one of the valves 116 being illustrated. The valve 116 includes a head 118 which is engaged with a seat 120 of the cylinder head 114 and a stem 122 which is guidingly disposed in a bore 124 formed in the upper part of the head 114.

For each of the valves 116, the head 114 is provided with a bore 126 therethrough through which there extends an elongated push rod 128. The push rod 128 is reciprocated in timed relation by a cam shaft (not shown) and serves to actuate the associated one of the valves 116.

Mounted on the head 114 and extending upwardly therefrom is a plurality of longitudinally aligned supports 130, only one of which is illustrated. Suitably journaled in the supports 130 is a rocker shaft 132 on which there is mounted for rocking movement a plurality of rocker arms 134. Only one rocker arm 134 is illustrated.

The rocker arm 134 is connected to the valve stem 122 by means of a fitting 136 which is identical with the fitting 46.

In order that the valve 116 may automatically be returned to a "closed" position, there is provided a valve return spring 138. The valve return spring 138 extends between the rocker arm 134 and the head 114. Secured to the upper surface of the head 114 is a retainer 140 for the lower end of the valve spring 138. A similar retainer 142 is connected to the underside of the rocker arm 134 by means of a pin 144 seated in a socket 146 in the rocker arm 134, as is best shown in Figure 8. It is to be noted that the spring 138 has been shifted to a position between the rocker shaft 132 and the valve 116 from its position of Figure 1.

Referring now to Figure 7 in particular, it will be seen that the left end of the rocker arm 134 is bifurcated to provide an upper flange 148 and a lower flange 150, the flanges 148 and 150 being disposed in spaced, parallel

relation. The flange 148 is provided with an internally threaded bore 152 which extends therethrough normal to the plane thereof and which has adjustably threaded therein a threaded shank portion 154 of a stop member 156. The threaded shank portion 154 is provided with a lock nut 158 to retain the stop member in an adjusted position.

The lower flange 150 is provided with a plug 160 which is removably threadedly engaged therein and which is provided with a bore 162 aligned with the internally threaded bore 152. Slidably disposed within the bore 160 is a shank 164 of a follower 166 for the upper end of the push rod 128. The follower 166 is provided with a spherical head 168 on the lower end of the shank 164, the head 168 being seated in a socket 170 formed in the upper end of the push rod 128.

In order that the spherical head 168 may be retained in the socket 170 at all times, there is provided a spring 172 which underlies the flange 150 and extends between the plug 160 and the spherical head 168. A spring retainer 174 is carried by the lower part of the shank 164 and rests upon the spherical head 168.

In order to assure the complete closing of a valve, it is necessary that there be provided a slight play in the valve train to compensate for elongation due to temperature changes. On the other hand, there should not be too much play in the valve train, inasmuch as this would permit battering of those parts between which there is relative movement. By permitting the upper end of the shank 164 to strike the stop member 156 so as to act as the tappet of the valve train, the desired adjustment of the valve train may be obtained by adjusting the position of the stop member 156 with respect to the upper end of the shank 164.

At this time it is pointed out that the adjustable connection between the rocker arm and the push rod will not be limited to the spring arrangement of Figure 6, but may be used in conjunction with the rocker arm 42 and the spring arrangement of Figure 1.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to falling within the scope of the invention as claimed.

What is claimed as new is as follows:

1. A valve train assembly for internal combustion engines comprising a rocker arm shaft, a rocker arm mounted on said rocker arm shaft, first means on the underside of said rocker arm at one end thereof for engaging a push rod, second means on the underside of

said rocker arm at the opposite end thereof for positive connection to a valve, and spring means engaged with said rocker arm for urging said rocker arm to a valve closing position, said second means including a universal joint whereby a valve connected to said rocker arm is free to rotate while being positively actuated by said rocker arm.

2. A valve train assembly for internal combustion engines comprising a rocker arm shaft, a rocker arm mounted on said rocker arm shaft, first means on the underside of said rocker arm at one end thereof for engaging a push rod, second means on the underside of said rocker arm at the opposite end thereof for positive connection to a valve, said second means including a ball member having an attaching rod and a socket member having an attaching rod, said ball member being seated in said socket member with said attaching rods extending generally in opposite directions.

3. A valve train assembly for internal combustion engines comprising a rocker arm shaft, a rocker arm mounted on said rocker arm shaft, first means on the underside of said rocker arm at one end thereof for engaging a push rod, second means on the underside of said rocker arm at the opposite end thereof for positive connection to a valve, said second means including a ball member having an attaching rod and a socket member having an attaching rod, said ball member being seated in said socket member with said attaching rods extending generally in opposite directions, said socket member including a plurality of ball elements engaging said ball member.

4. A valve train assembly for internal combustion engines comprising a rocker arm shaft, a rocker arm mounted on said rocker arm shaft, first means on the underside of said rocker arm at one end thereof for engaging a push rod, second means on the underside of said rocker arm at the opposite end thereof for positive connection to a valve, and spring means engaged with said rocker arm for urging said rocker arm to a valve closing position, said second means including a ball member having an attaching rod and a socket member having an attaching rod, said ball member being seated in said socket member with said attaching rods extending generally in opposite directions.
